UNITED STATES PATENT OFFICE.

ALVIN C. GODDARD, OF RICHMOND HILL, NEW YORK.

METAL DOOR AND THE LIKE.

Application filed October 7, 1925. Serial No. 61,008.

My invention is particularly applicable to metal door constructions, and objects of my invention are to simplify the construction and decrease the cost of manufacture of such doors, and at the same time to provide a door which will be strong and rigid and durable. Other objects will be apparent from the following particular description.

In accordance with my invention I provide 10 across the inner edges of the U-shape sheet metal stile and rail members, a metal strip which spans the space between the sides of the members and may be secured thereto, as by spot welding, and which has a longitudinal 15 groove in the plane of the space between the adjacent edges of the moldings within which the edge of the panel is received. The moldings may be integral with the stile and rail and terminate sufficiently short of the ends of 20 the members to allow the ends of the members to overlap and be secured together, as by spot welding. Ordinarily the stile will overlap the ends of the rail so that the folded over ends of the overlapping member will be at the 25 top and bottom of the door.

If wooden fillers for the stiles and rails are used, they are grooved to accommodate the panel receiving channel of the metal strip, and are also grooved at their corners to allow 30 the overlapped ends of the rail to be set in to provide flush surfaces, and also to accommodate the folded over ends of the stile. Corner reinforcing pieces may be used for the moldings. These will correspond in shape to the 35 miter joint of the moldings and will underlie the joint, and may be secured, as by spot welding, to one or both of the members.

My invention includes other features which will appear from the following description. 40 I shall now describe the illustrated embodiments of my invention and shall thereafter point out my invention in claims.

Fig. 1 is a face elevation of a corner of a door embodying my invention.

Fig. 2 is a section of the same on line 2—2 of Figure 1.

Fig. 3 is a section of the same on line 3—3 of Figure 1.

Fig. 4 is a view similar to Figure 1 with the 50 stile and panel removed and the rail partially in section.

Fig. 5 is a section on line 5—5 of Figure 4.

Fig. 6 is a sectional elevation of the parts shown in Figure 1 with the stile removed.

Fig. 7 is an inner side elevation of the stile.

Fig. 8 is a side elevation, partly in section,

of all the parts included in the assembly of Figure 1, except for the panel, the parts being shown disassociated.

Fig. 9 is a detail in perspective of the corner reinforcing piece on an enlarged scale. 60

Fig. 10 is a partial end elevation and partial section of one of the sheet metal members with the panel in place and showing a modified form of channelled spreader strip. 65

Fig. 11 is a detail in perspective of a short length of the spreader strip shown in Figure 10.

Both the stile 1 and the rail 2 are sheet metal members folded to U-shape. These two sheet 70 metal members have their ends joined at the corner of the door in overlapping relation. In the form shown the ends of the rail are overlapped by the metal of the stile. The molding is shown as integral with the sheet 75 metal members, the extended edge portions of which converge to form the moldings. The moldings of the rail are designated by the characters 2^a, while the moldings for the stile are designated by the characters 1^a. These 80 moldings terminate sufficiently short of the ends of the sheet metal members to meet when the members are joined, as shown in Fig. 1.

The overlapped ends 2^b and 2^c of the rail 2, which are the extensions beyond the end of the moldings 2^a, are comparatively short and are set in substantially the thickness of the metal so that the surface of the stile is flush with that of the rail. The ends of the stile 1 beyond the ends of the moldings 1^a are sufficiently long to cover the ends 2^b and 2^c of the rail, and to allow of their extremities being folded down to close the end of the stile in a plane flush with that of the bottom of the rail. The overlapping portions of the stile will be 85 secured to the ends of the rail in any suitable way, as by spot welding. 90

Spanning the inner edges of both the rail and the stile is a spreader strip 3. In the form shown in Figs. 1 to 8, this spreader strip 100 has its ends flanged, and these flanges are secured, as by spot welding, to the inner faces of the sheet metal members just back of the moldings. These spreader strips 3 serve as receiving members for the edges of the panel 4 which is also metal covered, and for this purpose they are provided with central longitudinal channels which are in the plane of the spaces between the adjacent ends of the opposing moldings. This provides a rigid 105 anchoring for the panels and takes the supporting strain for the panels largely off the 110

inner edges of the molding within which the edge of the panel is commonly received.

In order to brace and reinforce the moldings at the joints or corners, I employ corner reinforcing metallic members 5, one of which is shown enlarged in Fig. 9. This reinforcing piece is disposed against the inner face of the adjacent ends of the moldings at each corner, and it has two flanges one or both of which may be secured to the inner face of the sheet metal member, as by spot welding. In Figs. 4 and 8 these corner pieces are shown as secured only to the rail 2. The spreader strips 3 terminate sufficiently short of the ends of the molding to accommodate the corner pieces 5 at the corners when the rail and stile are assembled.

It is optional with my construction whether or not wooden fillers be used for the rails and stiles. I have shown such fillers in the illustrated construction. The stile filler 6 and the rail filler 7 are rabbeted together at the corner and are shown as permanently joined. Along their inner edges these fillers are provided with longitudinal grooves 8 to receive the channels of the spreader strips 3, and the outer faces of these edges are cut out to receive the flanges of the spreader strips 3. On each side of the rail filler 7 is provided a vertical groove 9 to receive the set in ends 2^b of the rail, and these grooves 9 are joined at the bottom by a corresponding groove to accommodate the bottom overlapped end 2^c of the rail. Also there is provided an external groove 10 to receive the folded over ends of the stile and thus allow the surface of the bottom and top edges of the door to be flush throughout.

It will be seen that there are a relatively small number of parts which are easily assembled and which provide a rigid construction when assembled. The wooden frame work of the door, if one is used, is first constructed and one corner is joined together as shown in Figs. 4 and 8. The spreader strips 3 will then be applied to the inner edges of the wooden stile and rail members which are joined together, as the member 3 is shown applied to the stile filler 6 in Fig. 4. The rail members 2 with the corner pieces 5 secured thereto will then be slipped on over the wooden rail pieces 7, and finally the sheet metal cover 1 of the stile will be slipped on from the free end of the wooden stile 6 until the molding pieces 1^a join the molding pieces 2^a. The ends of the sheet metal stile 1 will then be bent over the end of the stile, the overlapping edges being depressed in the groove 10 sufficiently to provide a flush surface. Then the sheet metal members 1 and 2 are spot welded to the spreader strips 3, and the member 1 will be also spot welded to the ends 2^b of the member 2. Also, if desired, the member 1 may be spot welded to the underlying flange of the corner piece 5

although this is usually unnecessary. The panel 4 will then be inserted through the moldings until its two edges are seated within the grooves of the spreader strips 3. The other stile and rail may then be similarly assembled and fitted over the panel and joined to the ends of the first assembled section and the overlapping ends be spot welded. If there are intermediate rail sections, they will, of course, be first applied before the two halves of the frame sections are joined.

In Figs. 10 and 11 there is shown a slightly different construction of spreader strip, designated by the reference character 3^a. This is made of somewhat heavier metal than the strip 3 and therefore it does not have its edges flanged, but is instead directly spot welded to the side pieces of a sheet metal member. The heat incident to the spot welding is apt to deform the first bead of the moldings, and therefore it is preferable to punch down the metal at intervals along the strip 3^a as shown at 3^b, and spot weld at these depressed points.

Other modifications in the specific construction shown in the drawings and above particularly described will readily occur to those skilled in the art within the principle and scope of my invention.

I claim:

1. In a metal door, sheet metal U-shape stile and rail members joined together at their ends in overlapping relation and having their edge portions converging to form integral moldings terminating sufficiently short of the ends of the members to meet when the members are joined, and a corner reinforcing piece underlying the meeting ends of the moldings, and having portions thereof conforming in shape to said moldings whereby the corner piece reinforces the corner structure including the molding portions thereof.

2. In a metal door, sheet metal U-shape stile and rail members joined together at their ends with the stile member overlapping the end of the rail member with their edge portions converging to form integral moldings meeting in a miter joint, the overlapped ends of the rail members being set in substantially the thickness of the metal and the overlapping portion of the stile being welded thereto with the surfaces flush, and a corner reinforcing piece conforming in shape to the moldings underlying the meeting ends of the moldings in contact with inner surfaces thereof and secured to one of the members.

3. In a metal door, sheet metal U-shape stile and rail members joined together at their ends in overlapped relation and having their edge portions converging to form integral moldings terminating sufficiently short of the ends of the members to meet when the members are joined, the overlapped member having its ends which are continued beyond the molding set in substantially the thickness of

the metal, and the overlapping member having its ends continued beyond the molding sufficiently far to receive the end of the overlapped member and be folded over to close 5 the end and a metal strip spanning the members back of the molding portions and having a central longitudinal channel to receive the edge of a panel disposed between the adjacent edges of the moldings and having depressions along its side edges adapted to be 10 secured to the adjoining members.

4. In a metal door, sheet metal U-shape stile and rail members joined together at their ends in overlapping relation and having their 15 edge portions converging to form integral moldings terminating sufficiently short of the ends of the members to meet when the members are joined, a corner reinforcing piece underlying the meeting ends of the 20 moldings, and a metal strip spanning the members back of the molding portions and having a central longitudinal channel to receive the edge of a panel disposed between the adjacent edges of the moldings.

5. In a metal door, U-shape sheet metal stile and rail members joined together at their ends with the stile member overlapping the rail member, the rail member having its overlapped ends set in to provide flush surfaces 25 and the ends of the stile member being

folded over to close the end of the stile, a metal strip secured to and spanning the open edges of each member and having a central longitudinal panel-receiving channel, and wooden fillers for the two members joined 35 at their ends and having their sides grooved to accommodate the said set in ends and having at the outer corner a longitudinal groove to accommodate the folded over ends of the stile and having along their inner edges longitudinal grooves to receive the channel of 40 the said metal strips.

6. A spreader strip for use in sheet metal doors or the like, comprising a metal strip of sufficient width to span the space between the sides of a door member and having depressions long its side edges adapted to be secured to the sides of said door member.

7. A spreader strip for use in paneled sheet metal doors or the like, comprising a 50 metal strip of sufficient width to span the space between the sides of a door member, said strip being formed with a central longitudinal channel to receive the edge of a panel and having depressions along its side edges 55 adapted to be secured to the sides of the said door member.

In witness whereof, I hereunto subscribe my signature.

ALVIN C. GODDARD.
